[57] CLAIM

The ornamental design for a retractable eraser, as
shown and described.

DESCRIPTION

FIG. 1 is a right side elevational view of a retractable
eraser showing my new design with the eraser in a fully
retracted state, the left side being the same in appear-
ance as the right side;

FIG. 2 is a front elevational view thereof;

FIG. 3 is a rear elevational view thereof;

FIG. 4 is a bottom plan view thereof;

FIG. 5 is a top plan view thereof; and,

FIG. 6 is a front elevational view thereof with the
eraser in a partly extended state.The characteristic feature of the design resides in the
particular marblized pattern on the eraser casing's sur-
face.FIG. 5
